J. C. BROADLEY, OF FRANKLIN, NEW JERSEY, ASSIGNOR TO HIMSELF AND JAMES STOUT, OF SAME PLACE.

Letters Patent No. 97,868, dated December 14, 1869.

IMPROVED DRILL FOR BORING POLYGONAL HOLES

The Schedule referred to in these Letters Patent and making part of the same

To all whom it may concern:

Be it known that I, J. C. BROADLEY, of Franklin, in the county of Essex, and State of New Jersey, have invented a new and improved Drill for Boring Polygonal Holes; and I do hereby declare that the following is a full, clear, and exact description thereof, which will enable others skilled in the art to make and use the same, reference being had to the accompanying drawing, forming part of this specification, in which—

Figure 1 represents a face view, partly in section, of my improved drill.

Figure 2 is a side view, partly in section, of the same.

Figure 3 is a horizontal section of the same, taken on the plane of the line $x\ x$, fig. 1.

Figure 4 is a horizontal section of the same, taken on the plane of the line $y\ y$, fig. 1.

Figure 5 is an inverted horizontal section of the same, taken on the plane of the line $z\ z$, fig. 1.

Similar letters of reference indicate corresponding parts.

This invention relates to a new implement for boring polygonal, oval, star-shaped, or holes of other suitable form, in metal, wood, or other material.

The invention consists chiefly in arranging the pattern which regulates the shape of the hole to be bored on the upper part of the drill-shank, and in having the bit-shanks, which are pivoted to the lower part of the drill-shank, held by means of springs against the inner edges of the inverted cup-shaped pattern. As the drill-shank revolves in the stationary pattern, the bit-shanks and bits are carried around with it, but are constantly held against the rim of the pattern to travel in a course of the same form as the pattern, thereby producing the required perforation.

The invention also consists in making the length of the bit-shank adjustable, so that the size of the hole may be increased or reduced without varying its form; also, in a new manner of pivoting the bit-shanks, if two are used, and of securing the bits in the same.

A, in the drawing, represents the drill-shank or central shaft of my improved drill.

At its lower end it carries a block, a , to which the bit-shanks B B are pivoted.

The bit-shanks are L-shaped levers, fitted with their lower arms into recesses, cut from below into the block a .

The pivot-pin b , of each lever B, is near the outer angle formed by the arms of the same, and passes entirely through the block a , and through a curved slot, c , of the other lever, as in fig. 1, so that each lever can swing on its own pivot, although that of the other lever passes through it.

C C are the bits, secured respectively in the lower ends of the levers B B.

Their upper ends are dovetailed, and fitted into corresponding recesses of the levers, as indicated in fig. 3.

Screws, $h\ h$, serve to retain the bits in place, they

being fitted through the sides of the levers to bear with their ends against the bits.

The block a has apertures, $d\ d$, to allow the insertion and removal of the screws h .

The upper ends of the levers B are, by means of springs $e\ e$, held against the inner side of the rim of an inverted pattern-cup, D.

This pattern-cup is hung loose upon the shaft A, and is of quadrangular or such other suitable form as the hole to be cut.

When the drill-shank is revolved, the bits and bit-shanks are revolved with it, but are at the same time swung in and out, as their upper ends are brought in contact with the inner or outer parts of the pattern-cup, the said cup being held stationary while the drill is revolved.

The drills will thereby produce holes of the required shape.

In order to avoid friction, I have arranged a friction-roller, F, at the upper end of each lever B, to roll against the rim of the pattern-cup.

Such rollers may, however, be entirely omitted, or in their place square or other blocks may be swivelled to the levers, for the purpose of following into the corners of the pattern-cup, and thereby guiding the bits with great exactness.

The size of the holes can be increased or diminished either by adjusting the bits longitudinally in the sockets of the levers B, or by regulating the lengths of the said levers.

For this purpose, each lever B is made of two parts, of which one or both are slotted, and connected by a bolt, g , so that they can be extended or contracted.

The bits cut only with their outer edges, which are sharpened in the manner indicated in fig. 4.

Instead of two or more bits, the device may be used with but one, by extending the drill-shank down slightly below the lower end of the bit, and pointing it, so that it will form a centre on which the bit can revolve.

Such extension of the drill-shank may also be used in connection with two or more bits.

The pattern-cups may be readily removed, and replaced by one of different shape.

Each lever B may also be jointed, to be transversely adjustable.

In that case, one arm has a transverse slot, i , and the other a screw or pin, j , fitted through the same, as shown in fig. 1.

By the lateral adjustment, the size of the hole cut by the bits can also be regulated.

Having thus described my invention,

I claim as new, and desire to secure by Letters Patent—

The combination of two or more bits C C, with a pattern-cup, D, and spring-levers B B, the said parts being arranged and operated in the manner described.
